CALIFORNIA.

ART OF PAVING.

1,041,578.

Specification of Letters Patent.

Patented Oct. 15, 1912.

Application filed May 5, 1909. Serial No. 494,127.

To all whom it may concern:

Be it known that we, JOHN A. BELL,
GEORGE R. WILTON, and GEORGE P. GRIFFITH,
residing at Los Angeles, in the county of
5 Los Angeles and State of California, have
invented new and useful Improvements in
the Art of Paving, of which the following
is a specification.

This invention relates to improvements in
10 the art of paving roads and streets; and it
has for its object to provide more perfect
paving constructions and formations with
respect to durability, life, appearance, facility
15 in installation and repair, and general
serviceability and efficiency.

With the above and other objects in view,
the invention consists in the novel provi-
sion, organization, formation, construction,
20 association, inter-relation and relative ar-
rangement of parts, elements and features,
all as hereinafter described, shown in the
drawing, and finally pointed out in claims.

In the drawing; Figure 1 is a transverse
25 sectional view, partly in full lines, of a por-
tion of a roadway in and upon which rail-
way rails are installed, the portion of the
roadway between the rails being organized
30 to embody the improvements in paving con-
stituting the invention; Fig. 2 is an en-
larged isometric view of a paving element
essentially concerned in the improvements
35 constituting the invention, the same being
shown separate from the remaining features
with which the same is shown associated in
Fig. 1; and Fig. 3 is an enlarged isometric
40 fragmentary view, more fully developed, of
the construction and organization of parts
and features shown in Fig. 1; the disclosure
in this figure being partly in full lines and
partly broken away for clearness of illus-
tration.

Corresponding parts and features in all
the figures are denoted by the same refer-
ence characters.

45 Referring with particularity to the draw-
ing, A, A designate railway rails installed
in and upon a road-bed B in connection
and association with ties C, one of which
is shown in the drawing.

50 D designates by general reference a paving
extending between the rails A and or-
ganized in accordance with the invention.
The paving D comprises specifically,
55 spaced rail paving blocks a, a, a filler b
between each of the rail paving blocks a

and the adjacent rail A, a paving body c
extending transversely of the road-bed B,
between the paving blocks a and superposed
upon the road-bed B, and a filler d corre-
60 sponding to the filler b and disposed be-
tween and uniting adjacent paving blocks a
at each side of the road-bed; there being
two lateral series of paving blocks a ex-
tending respectively adjacent to the rails A;
65 the paving body c being of continuous for-
mation intermediate of the lateral series of
said paving blocks. As hereinafter specifi-
cally disclosed, the organization of the pav-
ing D, inclusive of the paving blocks a and
70 the paving body c and the fillers b and d
is of such constituent nature as to provide a
homogeneous inter-relation and cohesion of
all the elements and parts thereof.

Each of the rail paving blocks a consists
75 of a porous body 4, composed of baked clay
the consistency of which is substantially
that of a soft light red or salmon brick.
The porous body 4 is impregnated with a
filler 5, corresponding in nature with the
80 fillers b and d, which is homogeneously dif-
fused throughout said body 4 to the full ex-
tent of receptivity of the porous structure
of the latter. Portions of the globular mass
of the filler 5 are shown in Fig. 3; but it is
85 to be understood that the distribution of
such filler throughout the mass of the porous
body is uniform and even to the extent of
complete occupation of the interstices present
in said porous structure. The paving block
90 a, having the inherent characteristics above
set forth, comprises, in its aspects of con-
formation resultant upon the distribution
of the portions of its mass, two lateral body
95 portions, 6 and 7 respectively, and an in-
termediate body portion 8, the entirety be-
ing of integral formation, as above de-
scribed. The lateral body portions 6 and
7 are formed respectively for association
100 with the rail A and the paving body c.
The base portion 9 of the paving block is
of plane formation, and the top portion 10
of said block, or of the intermediate body
portion 8 thereof, extends in parallel rela-
105 tion thereto, being likewise of plane forma-
tion. The vertical dimension of the inter-
mediate body portion 8 is such that when
the paving block is installed in and upon
the road-bed B, the top portion 10 of the
110 former will lie substantially in the hori-
zontal plane of the crown of the rail A.

The lateral body portion 6 is of diminished vertical dimension, with relation to the corresponding dimension of the intermediate body portion 8, whereby said body portion 5 may project between the crown and the bottom flange of the rail and be accommodated in the space between the same closely adjacent to the vertical web of the rail. Said lateral body portion 6 is preferably 10 rectangular in cross-sectional formation, the upper surface portion thereof being connected with the top portion 10 of the intermediate body portion 8 by an inclined surface portion 11. The lateral body portion 15 7 has an inclined upper surface portion 12, and a vertical side facial portion 13, which latter is of less vertical dimension than the vertical side facial portion 14 of the lateral body portion 6. In contradistinction to the inclined upper surface portion 20 12 of the lateral body portion 7, the upper surface portion 15 of the lateral body portion 6 is horizontal or extends in a plane parallel with the plane of the top portion 10 of the block *a*.

The paving body *c* is massed in between the paving blocks *a* so that the upper or wearing surface of both of the same conform to the same plane, constituting a continuous 25 and unbroken surface portion; and the portion of the paving body *c* in contact with the inclined upper surface portion 12 of the lateral body portion 7 of the paving block *a* is complementary thereto in conformation, 30 establishing an inter-locking relation between the paving body *c* and the paving block *a*, opposing disruption of the paving block *D* by dislocation of the paving block.

The filler *d* is massed firmly between adjacent paving blocks *a*, as illustrated in Fig. 40 3; and the filler *b* is massed between each paving block and the web of the adjacent rail, extending between said web and the lateral body portion 6 of the paving block.

The paving so comprising the blocks *a*, the fillers *b* and *d*, and the paving body *c*, constitutes a continuous and unbroken unit filling the space between the rails A; all of the parts and elements of the paving being 45 50 homogeneously united, as follows from the specific preferred nature of the composition of matter common to all of the three fillers, that is the joint fillers *b* and *d* and the body filler 5, and the paving body *c*.

The essential constituent substance of each of the joint fillers *b* and *d*, the body filler 5, and the paving body *c*, is preferably asphaltum. The joint fillers *b* and *d* and the paving body *c* are preferably composed of 55 60 an asphaltum mixture of predetermined fineness. The body filler 5 preferably consists of asphaltum having less than two per cent. carbene, as determined by the test known in the art as the cold carbon tetrachlorid test. We have determined that in

order to properly penetrate the body 4 of the paving block *a*, with asphaltum, there must not be present in the asphaltum as much as two per cent. carbene; and that if a greater percentage of carbene is present in the asphaltum the latter will not be of proper fineness or purity to produce such constitution of the paving block as shall insure the highest efficiency thereof, both in service and in the homogeneous uniting of the paving block or blocks with the paving body *c* and the fillers *b* and *d*. In other words, proper coalescing or fusion of the paving body and the fillers *b* and *d*, and also the filler 5, does not result if a higher percentage of carbene is present in the asphaltum constituting the filler 5. If a higher percentage of carbene is present, the wearing surface of the paving block will be inferior, as the carbene penetrate to a lesser degree the paving block 70 75 body 4 than do the purer portions of the asphaltum. Therefore, if a higher percentage of carbene is present the exterior portions of the paving block are inferior with respect to durability and service efficiency, being 80 85 more brittle, frangible and friable, and possessing a lesser tendency to "heal" consequent upon indentation or other disruption. The melting point of the body filler 5 is predetermined not to exceed 170 degrees 90 95 Fah.; whereas the degree of heat present in the asphaltum mixture constituting the joint fillers *b* and *d*, and the paving body *c*, at the time of application of the same, is from 250 to 300 degrees Fah. When the paving 100 body *c* and the joint fillers *b* and *d* are applied to the paving blocks *a*, in plastic condition and at the temperature above recited, organizing the paving *D*, the heat of the asphaltum mixture of the elements *b*, *d*, *c* 105 is in part transmitted to the body filler 5 the temperature of which is elevated to a degree exceeding the melting point of said body filler, and the same is reduced to a liquid or plastic condition, with the result 110 that the molten body filler 5 and the joint fillers *b* and *d* and the paving body *c* cohesively unite, producing a homogeneous unitary mass including the filled paving blocks *a* and the paving body *c*, together 115 with the joint fillers *b* and *d*. It is manifest that the homogeneous formation of the completed unitary paving *D* may be broken up to permit detachment of the paving blocks *a*, for repair, by application of heat sufficient to fuse or melt the cohering joint fillers *b* and *d* and the body filler 5 and the paving body *c*.

The advantages predicated upon the use in service of the improvements in paving 120 125 constituting the invention will be readily understood from the foregoing description, taken in connection with the accompanying drawing and the following statement:

The rail paving blocks *a*, organized as de- 130

scribed, are of greatly increased durability with respect to paving blocks formed according to standard practices. When the vitrified paving block or brick is employed, 5 the brittleness of the same renders it framable to an objectionable extent, resulting in frequent fracture and dismemberment of the structure. The porous body 4 impregnated with the asphaltum filler 5 is capable 10 of withstanding extreme stresses of compression or impact without breakage, adapting it particularly for insertion adjacent to railway rails, which proximity of location requires the provision of an open space for the 15 wheel flanges as indicated in the drawing above the lateral body portions 6 of the paving blocks *a*. Indentations or other invasions of the paving block structure are to an extent self-healing under further 20 compression or impact, the asphaltum filler 5 effectively knitting together the disrupted porous fabric.

The conformation of the lateral body portion 7 of each paving block, together with its 25 homogeneous joining with the adjacent portion of the paving body *c*, provides and forms a locking inter-relation between these elements, making for unity and structural durability of the entirety. These results are 30 supplementarily effected by the homogeneous knitting of the joint fillers *b* and *d* and the filled paving blocks *a* with the paving body *c*.

A further advantage flowing from the employment of the paving block *a* impregnated as described, consists in substantial 35 freedom from the presence of objectionable dust due to the service attacks of vehicle wheels and other objects.

40 The entire paving *D* is highly durable and of long life, and has an inherent tendency

to preserve a proper surface conformation and condition.

We do not desire to be understood as limiting ourselves to the specific provision, composition, construction, formation, association, and combination of parts, elements and features shown and described as embodied and utilized in the practice of the invention; but reserve the right to vary the same, in 45 adapting the invention to varying conditions of use, without departing from the spirit of the invention and the terms of the following 50 claims.

Having thus described our invention, we 55 claim and desire to secure by Letters Patent:—

1. In a pavement, a porous block impregnated with a filler having a relatively low melting point, and a plastic body adapted 60 to coalesce with the filler and applied at a higher temperature than the melting point of the filler, whereby the plastic body and porous block are bonded together.

2. A porous block impregnated with a filler having a relatively low melting point, 65 and a plastic body applied at a higher temperature than the melting point of the filler, whereby the plastic body and porous block are bonded together, both the filler and the plastic body having asphalt as the essential 70 constituent thereof.

In testimony whereof, we have signed our names to this specification in the presence of two subscribing witnesses.
